United States Patent Office

Des. 224,186
Patented July 11, 1972

224,186

SASH

Melvin V. Zakarin, 23 Ogden Lane,
Englishtown, N.J. 07726

Filed July 20, 1970, Ser. No. 24,017

Term of patent 3½ years

Int. Cl. D2—07

U.S. Cl. D2—385

FIG. 1.

FIG. 2.

FIG. 3.

FIG. 4.

FIG. 1 is a front perspective view of a sash showing my new design, the decorative design unit being repeated the length of the sash as indicated;

FIG. 2 is a front plan view thereof shown broken away for convenience of illustration;

FIG. 3 is a rear plan view thereof;

I claim:

The ornamental design for a sash, substantially as shown and described.
